[57] CLAIM

The ornamental design for a set of railroad tie clamps for use in landscaping, as shown and described.

DESCRIPTION

FIG. 1 is a perspective view of a set of railroad tie clamps for use in landscaping showing my new design, with a connector being shown separately;
FIG. 2 is a front elevational view thereof, the rear being a mirror image of the front shown in FIG. 2;
FIG. 3 is a side elevational view thereof, the side opposite being a mirror image of the side shown in FIG. 3;
FIG. 4 is a top plan view thereof; and,
FIG. 5 is a bottom view thereof.

FIG. 4

FIG. 5

FIG. 2

FIG. 3
